UNITED STATES PATENT OFFICE.

IRA W. ARMSTRONG AND CHARLES A. PLAMADORE, OF BELVIDERE, ILLINOIS.

AUTOMATIC AIR-COUPING.

1,202,258.

Specification of Letters Patent.

Patented Oct. 24, 1916.

Application filed August 23, 1912, Serial No. 716,698. Renewed May 9, 1916. Serial No. 96,431.

To all whom it may concern:

Be it known that we, IRA W. ARMSTRONG and CHARLES A. PLAMADORE, citizens of the United States, residing at Belvidere, in the county of Boone and State of Illinois, have invented new and useful Improvements in Automatic Air-Couplings, of which the following is a specification.

Our invention relates to automatic air couplers for railroad cars, the object of the invention being to provide a device which will be efficient in operation, its construction being such that failure to operate under the proper conditions, and any danger of leakage of air, are impossible.

Further objects of the invention will appear as the following specific description is read in connection with the accompanying drawings, which form a part of the application, and in which—

Figure 1 is a front elevation. Fig. 2 is a side elevation. Fig. 3 is a sectional view on the line 3—3 of Fig. 1, and Fig. 4 is a transverse sectional view taken on the line 4—4 of Fig. 2.

Referring to the drawing, the numeral 1 designates the car body to the under surface of which and adjacent one end thereof are secured the parallel, transverse hangers 2 and 3, the latter being located near the end of the car. The hanger 2 is provided with a horizontal, cylindrical opening 4 in alignment with a rectangular opening 5 provided in the hanger 3. A tubular body 6 provided with the longitudinal opening 7 and having its inner portion cylindrical in shape, as at 8, its outer portion rectangular in shape, as at 9, and a peripheral flange 10 formed between the inner and outer portions, is slidably mounted within the openings of the hangers 2 and 3, as clearly shown in Fig. 2 of the drawing. In this position the flange 10 abuts the inner surface of the hanger 3 so as to limit the outward motion of the member 6, and a helical spring 10^a interposed between the hanger 2 and the flange 10 tends to normally hold the member in its extended position. The extremities of the member 6 are screw threaded as at 11 and 12, the inner extremity being adapted to receive the end of the train pipe 13, and the outer extremity adapted to receive the end of a valve 14. The plug 15 of this valve is provided with a stem 16 whose outer portion is bent laterally as at 17. The extremity of the portion 17 is pivoted to a

bracket 18 mounted on the under surface of the car body at one side of the valve when in its normal position. A cylindrical continuation 19 of the tubular member is 60 threaded into the opposite end of the valve as at 20 and has its outer portion enlarged to form a head 21 whose walls diverge outwardly and whose outward face 22 presents the form of an ellipse, the longitudinal axis 65 of the elliptical face lying in a horizontal plane. A passageway 23 is provided within the head 21 as a continuation of the opening 7 of the tubular member and it is in alignment therewith. A recess 24 is provided in the outer portion of the head 21 so that its walls converge inwardly to form a socket, which communicates with the passageway 23 and is provided at its point of juncture therewith with a peripheral groove 70 25. A ring 26 of rubber or some such elastic material is mounted within the groove 25 for a purpose hereinafter specified. An angularly extending passageway 27 leads laterally from the passageway 23 and has its 75 outer portion extending forwardly as at 28. This portion of the passageway is slightly enlarged and is screw threaded for the reception of the externally screw threaded inner extremity 29 of a tubular projecting 80 member 30 whose central opening 31 communicates with the inner portion 28 of the passageway 27. A buffer member 32 of rubber or some such material of suitable thickness, is mounted on the face of the head 90 21 and surrounds the projecting member 30 which passes through an aperture 33 therein. A peripheral flange 34 formed on the member 30 adjacent its threaded portion is adapted to engage the outer surface of the 95 member 32 to hold the same securely in position. The outer end of the member 30 is rounded as at 35 and is adapted to be received by the socket of a coacting coupler head similar to the socket 24, so that the 100 elastic ring thereof, through which the extremity of the member 30 will be forced, will form an airtight joint. The buffer member 32 serves a two-fold purpose, it being a buffer to relieve the shock caused by the 105 meeting of the coacting coupler heads, and also serving to make an airtight joint between the projecting member 30 and the threaded portion of the passageway 27 in the head 21.

The coupling devices are to be positioned upon the under surfaces of their respective

ends of the car bodies so that when two co-acting coupler heads abut each other, the projecting member of one will be received within the socket of the other, the inwardly converging wall of the sockets serving to guide the extremities of the projecting members into position within the elastic rings in case the coupler heads are slightly out of alinement, each projection being of such diameter as to be wedged securely within the corresponding ring, thus affording an airtight joint despite any lateral movement of the coupler heads relatively. When two co-acting coupler heads come together, the tubular bodies thereof will slide inwardly through their respective hanger openings against the action of their helical springs, and in so doing the valve stems will be rotated so that air communication will be open when the tubular bodies are in their retracted position which is rendered permanent by the locking of the car couplers. The valves will remain open until the cars are uncoupled and the air coupler heads are permitted to move outwardly. During such operations the rectangular portion 9 of the tubular body 6 moves within the rectangular opening 5 of the hanger 3 and, by preventing rotation of the body, sustains the head 21 in its position with its center of gravity displaced with respect to the longitudinal axis of the body 6, the threaded connections between the portions

of the body 6 being such that the weight of the displaced portion of the head 21 tends to tighten said connections.

We claim:

A device of the kind described in combination a support, brackets carried thereby, a tube slidably mounted in said brackets, a socket bearing formed integrally upon one end of said tube and having a laterally inclined extension, said bearing being formed with an outwardly flaring chamber in a line with said tube the inner part forming a channel of uniform diameter, uniformly cylindrical part being formed with an annular groove at the junction with the flaring chamber, a resilient ring snugly countersunk in said annular groove, said bearing being formed with an inclined chamber parallel with said inclined extension the outer part of which being in alinement with said tube, a connecting plug threaded into the alining part of said last mentioned chamber, a shoulder on said plug, and a rubber gasket engaging said plug and engaged by said shoulder, being of larger diameter than the latter.

In testimony whereof we affix our signatures in presence of two witnesses.

IRA W. ARMSTRONG.
CHARLES A. PLAMADORE.
